UNITED STATES PATENT OFFICE.

GILBERT ELPHINSTONE HARVEY SPILLER, OF EAGLEHURST, CHAGFORD, ENGLAND.

GUARD FOR CIRCULAR SAWS.

1,422,316.

Specification of Letters Patent. Patented July 11, 1922.

Application filed October 3, 1921. Serial No. 504,940.

To all whom it may concern:

Be it known that I, GILBERT ELPHINSTONE HARVEY SPILLER, a subject of the King of Great Britain, residing at Eaglehurst, Chagford, Devonshire, England, have invented 5 new and useful Improvements in Guards for Circular Saws, of which the following is a specification.

This invention relates to guards for circular saws which work in a slot in a saw bench.

According to this invention the guard consists of a casing fixed to the saw bench and a drawer sliding in the casing and having two plates on each side, spaced apart in order to 15 leave a gap between the plates. The side plates are mounted upon angle irons which are secured together by bolts passing through tubes whose ends abut against the angle irons. The drawer has an end plate secured to the 20 side plates which plate may be provided with a handle.

A metal plate may be secured to the saw bench to form a guide for the angle irons. The casing has two side plates and a top of 25 greater length than the width of the side plates.

The accompanying drawing shows a guard made in accordance with this invention.

Figure 1 is a side elevation, Figure 2 a 30 plan, Figure 3 an end elevation and Figure 4 a perspective view.

A saw bench *a* has a slot *b* through which a circular saw *c* extends. To the bench *a* is secured by bolts *d* a casing having two side 35 plates *e* and a top plate *f* of a length greater than the width of the side plates *e* so that it extends above the saw *c*. A drawer slides in the casing, which drawer is constructed of two angle irons *g* secured together at each 40 end by bolts *h* passing through tubes *j* whose ends abut against the angle irons. To each angle iron *g* are secured plates *k* and *l*, a space being left between the plates as shown. An end piece *m* is secured to the plates *l* and 45 the end piece *m* is provided with a handle *o* by which the drawer is moved.

A guide for the angle irons, consisting of a

plate *p* is secured to the bench *a* by a bolt *q*. In operation the log to be cut is placed in the gap between the plates *k* and *l* and the 50 drawer is pushed towards the saw *c* until the teeth of the saw appear in the space between the plates *k* and *l*, when the saw will begin to cut the log. When the log has been cut the drawer is pulled back, the saw being 55 covered by the guard throughout the operation.

What I claim is:—

1. A guard for a circular saw working in a slot in a saw bench, consisting of a casing 60 fixed to the bench and a drawer adapted to slide in the casing and having two plates spaced apart on each side.

2. A guard for a circular saw working in a slot in a saw bench, consisting of a casing 65 fixed to the bench and having two side plates and a top plate of a length greater than the width of the side plates, and a drawer adapted to slide in the casing and having two plates spaced apart on each side.

3. A guard for a circular saw working in a slot in a saw bench, consisting of a casing 70 fixed to the bench and a drawer adapted to slide in the casing and having two plates spaced apart on each side and secured to an angle iron on each side, the angle irons being secured together by bolts passing through tubes whose ends abut against the angle irons.

4. A guard for a circular saw working in a slot in a saw bench, consisting of a casing 80 fixed to the bench, having two side plates and a top plate of a length greater than the width of the side plates, and a drawer adapted to slide in the casing and having two 85 plates spaced apart on each side and secured to an angle iron on each side, the angle irons being secured together by bolts passing through tubes whose ends abut against the angle irons.

In testimony that I claim the foregoing as my invention I have signed my name this 90 13th day of September, 1921.

GILBERT ELPHINSTONE HARVEY SPILLER.
